UNITED STATES PATENT OFFICE.

BENJAMIN H. ALLEN, OF BEAUMONT, TEXAS.

SERVING APPARATUS.

Application filed June 6, 1927. Serial No. 196,797.

My invention relates to an improvement in serving apparatus for use particularly in serving patrons at lunch counters or drink stands where the food or drinks are delivered 5 to the occupants of automobiles or similar conveyances.

It is desired to provide a serving device for use in delivering a tray with articles of food or drinks thereon from one point to another with automatic means for controlling 10 the movement of the tray.

It is desired to provide a device of this character whereby the operation of the tray from one point to another may be controlled 15 entirely by gravity, when desired, means being contemplated, however, for mechanically conveying the tray wherever desired.

The invention also contemplates the provision of a particularly effective type of tray 20 adapted to be used upon a serving device and adapted to be connected with the body of the car or automobile in which the patrons are seated.

It is also desired to provide a means for 25 maintaining the tray in approximately horizontal position, said means operating automatically to compensate for the position of the track upon which it runs.

The invention further contemplates the position of a frame or track with a tray slideable 30 thereon from one end to the other and means whereby the track or frame may be tilted to allow the sliding of the serving tray from one end to the other, and automatic means to control the position of the tray.

The invention resides largely in the particular construction and arrangement of the parts making up the invention and reference is made to the drawing herewith wherein a 40 preferred embodiment of the invention is disclosed. Fig. 1 is a side view largely in central vertical section on the line 1—1 of Fig. 4 and illustrating an apparatus employing my invention. Fig. 2 is a transverse section 45 on the line 2—2 of Fig. 1. Fig. 3 is an enlarged view in central longitudinal section of a releasing sleeve employed with the invention. Fig. 4 is an end view taken on the line 4—4 of Fig. 1. Fig. 5 is a vertical section 50 taken through the inner supporting leg of the frame. Fig. 6 is a bottom plan view of the serving tray, parts being broken away for greater clearness; and Fig. 7 is a top plan view of said tray. Like numerals of reference 55 are employed to designate like parts in all the views.

In carrying out my invention, I provide a central supporting frame upon which the trackway and its related parts may be pivoted for a tilting or rocking motion. The supporting frame comprises a post or pedestal 1 having a base 2 for attachment to any desired platform. The pedestal 1 is preferably of tubular construction. It has a shaft 3 telescoping therein. There is a spring 4 secured to said shaft and having an end 5 thereon projecting through an opening in the post and tending to hold the frame on said shaft 3 in adjusted position.

The shaft 3 projects through the head 6 of 70 the upper end of the post and is adapted to pivot therein. It is secured at its upper end to a T-shaped coupling 7, the lower end of which bears upon the head 6 of the post. It has two laterally extending arms 8 connected 75 by L-shaped couplings 9 to upright arms 10 which are connected at their upper ends to elbows 11, the horizontal portions of which furnish a bearing for a shaft 12 parallel with the arms on the lower side of the frame. The 80 frame thus constructed is approximately rectangular in shape, as shown in Fig. 4. It is supported pivotally by the shaft 3 at the lower end and may, therefore, rotate so as to swing the ends of the trackway from side to 85 side.

The upper shaft 12 may rock in its supports at each end. It furnishes a support for a track frame made up of an upper longitudinal track member 13 secured by a bracket 90 14 to the shaft 12 and rigid therewith. Its ends are connected by a specially formed elbow 15 to an upright 16 at one end and a sleeve 97 parallel therewith at the other end. The upright 16 is connected with a lower horizontal 95 frame member 17 by means of an elbow 18, similar in construction to the elbow 15. The opposite end of the track member 17 is connected to a fitting 19 of tubular construction by means of which it is joined to the lower end of the sleeve 97. The tubular track members 13 and 17 provide a support for the 100 operating mechanism connected with the operation of the tray shown at 20. The sleeve 97 at one end of the track frame is adapted to receive a supporting post 18 adapted to telescope within the sleeve 97 and having a series of circumferential grooves or notches 21 therein. It has at its lower end below the frame a forked foot 22 within which is journaled a roller 23 upon a pin 24. Said pin projects beyond the foot at each side and is 105 110

adapted to engage beneath guide rods 25 on each side of the foot. The roller 23 is adapted to rest upon a base member 26^a which, as shown in Fig. 5, has a step downwardly at 27 so that the movement of the frame laterally at the inner end will move the supporting post 18 from one level to the other. The shaft 24 upon the roller engages beneath the guide rods 25 during such movement.

10 The frame may be adjusted upon the post 18. It has toward the lower end of the frame a latch comprising two levers 26 which are pivoted together at 27 outside the frame member and having two inwardly extending arms 28 at the forward end, as shown in Fig. 2, to engage within the notches 21 in the post.

15 The arms 28 are held in latching engagement by means of a spring 29 between the outer handles of the levers 26. When the frame is to be adjusted vertically upon the post 18 the levers are compressed to throw the arms 28 out of engagement with the post and allow adjustment of the frame thereon, after which the levers may be released to 25 again engage within the adjacent notch or groove 21.

20 The tray is mounted upon an upright frame, indicated at 30. This frame is rectangular in shape and has two upright members 30, a top connecting member 31 and base member 32. The tray is mounted within this frame. The lower base member 32 of the frame is mounted upon forward and rearward rollers 33 bearing upon the trackway 35 formed by the lower track member 17. The upper member 31 of the frame has a roller 34 bearing against the upper track member 13. The frame may be connected at its forward side to a chain or other flexible member 35. Said chain may run beneath the track member 13 and through an opening in the upper elbow 15' about a pulley 36 therein and from thence back again within the track member 13 and around the pulley 36' at the other end within the elbow 15. The end of the chain is extended through the side of the elbow 15 and connected at 37 to the rearward side of the tray frame, as shown in Fig. 1. On each side of the roller 34 upon the tray frame 50 are bumpers 38 which may contact at each end of the track with rods 40 mounted resiliently within lugs 41 in the frame and acting both as shock absorbers and as contact members of an electric switch by means of which the operating motor is controlled.

55 The motor shown at 42 is mounted on the upper end of the elbow 15' and is connected through a gear 43 with the shaft of the pulley 36 so that the rotation of the motor will operate the chain by means of which the tray is moved. The motor is preferably a reversible motor so that the chain may be driven in either direction and may be controlled by operating switches of any preferred form. It is contemplated, however, that the switches

40 at each end of the frame will serve to throw the motor out of operation as soon as either of the posts 38 contact with the switch rod 40 at either end of the frame.

While I have shown the tray as being capable of operation by a motor, I do not contemplate attaching a motor of this type except in particular cases where the gravity system of operation would not be desirable. Under ordinary circumstances, I contemplate 75 using the gravity system entirely and running the tray from one end of the track frame to the other by merely tilting the frame on the shaft 12 as an axis. In such operation, the motor may be entirely eliminated, if desired. In this operation of the device I provide a weight 44 mounted upon a rod 45 secured to the lower side of the track frame 17. The weight is slideable on the rod 45 and may be adjusted into any desired position thereon 85 by set screw 46. It is desired that the inner end having the leg 18 thereon will be slightly heavier than the outer end and the predominance of weight may be governed by the sliding of the balance weight 44 along the rod. 90

The tray 20 is an approximately rectangular plate or supporting member and is preferably formed of two sections, an upper section 47 and a lower section 48 within which the upper section is slideable. The lower section has at the rearward side a series of openings 49 slightly to one side of the center line of the base and the upper member 47 of the tray has a rod 50, the forward end of which extends in front of the tray and has a short crank arm 51 thereon by means of which the rod may be rotated. The inner end of the rod 50 also has a crank arm 52 thereon with a downwardly extending finger or bolt adapted to extend through an opening in the tray 100 to engage within one of the openings 49 in the base member. Thus the upper tray 47 may be moved outwardly relative to the base and locked in adjusted position at any desired point relative to the base member. 110

This tray has downwardly extending lugs 53 thereon to receive a shaft 54 mounted in lugs 55^a in the lower frame portion 32. This allows the tray to be pivoted relative to the frame, as will be obvious. The position of the tray relative to the frame is regulated by a latch member 55, shown particularly in Fig. 6, secured on the lower side of the frame. It comprises a bar having blades 56 at each end. It is approximately S-shaped and is pivoted at 57 intermediate its ends. The blade members 56 at the ends of the latch member engage within notches 58 in the upright portions 30 of the frame, as shown in Fig. 1. A spring 59 holds the latching blades to engage with the notches 58 of the frame, preventing tilting of the tray relative to the frame while the latch is engaged. 115

The frame has on its forward and rearward sides releasing bolts 60 and 60'. These bolts 120

have wedge shaped heads thereon adapted to fit against the inner sides of the latch blades 56 and to be depressed so as to engage the edge of the latch member and force it laterally 5 away from engagement with the notches 58 in the frame against the action of the spring 59. The wedge shaped head of the releasing bolt is normally held resiliently away from the latching blade 56 by means of a spring 61 bearing against the upper edge 62 of the bolt at one end and against the supporting member of the frame at the other end.

The tray is mounted in its base and the base is automatically tilted to maintain the tray in a horizontal position by means of controlling fingers 63 at one end of the frame and 64 at the other end. Referring to the finger 63, it will be noted that it is mounted upon a sleeve 65 telescoping over a post 66 on the upper side of the fitting 19 of the frame. This sleeve 65 is connected with a rod 67 within the post 66 but is held resiliently upward away therefrom by means of the spring 68. The sleeve may be drawn downwardly upon the post 66 by means of a chain 69 secured to the lower end of the rod 67 and running around a pulley 70 within the fitting 19. The other end of the chain 69 is connected with the rod 71 which extends the full length of the lower track member 17 inside thereof and is connected at its opposite end by means of a chain 72 with a rod 73 in the upright 16. Said rod 73 is suspended by means of a tension spring 74 upon a pin 75 within the said upright 16. The rod 73 may be drawn downwardly against the tension spring 74 by means of the chain 72 engaging about the pulley 76. The finger 64 is mounted rigidly upon the rod 73 and is movable vertically within the slot 77 in the side of the upright 16.

The rod 71 has connected therewith midway between its ends a downwardly extending arm 78. As shown in Figs. 1 and 4 the arm 78 extends through a slot 79 in the track member 17 and projects through a block 80 mounted upon supports 81 rigidly within the frame member 7. The arm 78 is thus held approximately stationary, preventing any translating movement of the rod 71 relative to the stationary block 80. Thus, when the frame is tilted on the shaft 12 as an axis, the pendulum movement of the frame thereon will move the lower track 17 relative to the rod 71 and exert a pull in one direction or the other upon said rod, depending upon the direction of the tilting of the frame. Thus, when the inner end of the frame adjacent the motor is elevated a pull downwardly will be exerted upon the sleeve 65 and the finger 63 through the rod and the connecting means. This movement downwardly will force the finger 63 against the releasing bolt at 62 and serves not only to tilt the tray but to spread the latch members 56 out of engagement with the tray frame and allow the tray to be tilted and engaged in its new position.

tion with the frame member 30 to hold it in horizontal position while the frame itself is tilted.

When the tray is at the opposite end of the frame, the finger 64 will likewise engage the releasing bolt 60' and tilt and lock the frame in its proper position to maintain it horizontally at all times. 70

The pressure of the fingers 63 and 64 upon the releasing bolts of the tray will tend to hold the tray from movement along the track when the frame is tilted. To release the hold of the fingers 63 and 64 from the tray frame, I provide sleeves 82 connected within the rod 71 adjacent each end of the frame, as shown in Fig. 1. Referring to Fig. 3 the construction of this sleeve and its connection within the rod 71 will be noted. The sleeve 82 is closed at each end except for a central opening 83 to receive the sections of the rod 71. At one end the rod 71 has a head 84 slideable and rotatable within the sleeve. At the opposite end the rod 71 is provided with a laterally extending finger 85 which engages within a groove 86 on the inner surface of the sleeve. This groove is L-shaped having a transverse portion and a longitudinal portion. The finger 85 engaging within the transverse portion of the slot normally holds the flexible connection 69 or 72 to exert a pull downwardly upon the finger 63 or 64. Projecting through the track member 17 into each of said sleeves are set screws or bolts 87. The end of the bolt projects through a slot 88 within the sleeve.

Said slot is spirally arranged on the sleeve so that when the sleeve is moved longitudinally relative to the pin 87, the sleeve will be caused to rotate. Thus, when the frame is tilted in either direction, the movement of the rod 71 will tend to move the sleeve 82 and the pin 87 will thereby tend to rotate the sleeve. This rotation of the sleeve will carry the finger 85 upon the rod 71 around into the longitudinal arm of the slot 86 and allow the rod to have the effect of lengthening, thus releasing the pull thereof upon the latching fingers 63 or 64 so as to allow the tray to be moved away automatically. When the rod is again moved back into its original position the movement of the parts will be reversed the rod 71 will tend to push the finger inwardly in the sleeve and the finger 85 will again move into the transverse arm of the slot 86. 115

The frame member 30 of the tray has a laterally extending arm 89, shown in Fig. 4, which is adapted to engage with the door of the automobile upon which the tray is to be delivered. The said arm 89 has a latching finger 90 on its forward end which may be engaged over the door of the car to hold the end of the frame in position closely adjacent the car. The tray itself has a lateral arm 91 above the latching arm 89 and this arm 91 of the tray is made up of two parts which, as seen in Fig. 7, are engaged with the tray at 130

one end and their meeting ends normally will provide a loop handle for operating the tray and sliding it on the base member 48. When desired, however, the two parts of the handle 5 91 may be thrown downwardly in the middle so as to provide hooks to engage over the side of the car or any other convenient member to hold the tray in the position desired.

In the operation of the device, it is contemplated that the inner end having the post 10 18 thereon will be adjacent the serving stand and the tray will be at that end of the frame. The automobile will drive into a stall or marked off place on the pavement or upon 15 the ground adjacent the stand and the tray will then have the food or drink placed thereon and the inner end will be elevated by grasping a handle 92 and the latch member 26, raising the inner end of the frame along 20 with the supporting leg 18 and also swinging the frame on the upright axis 3 so as to throw the outer end of the trackway closely adjacent the car. As the frame is swung to bring the outer end toward the car the foot 22 will 25 move away from the step portion 27 of the supporting base. The tray will be then automatically released and the tilting of the frame upwardly at the inner end to carry the tray downwardly toward the opposite end 30 will automatically result in the operation of the mechanism just described to maintain the tray at an approximately level position within the frame 30. The operation of the releasing sleeve shown in Fig. 3 will release 35 the finger 63 and allow the tray to slide down the trackway to the opposite end. It will there engage with the finger 64 and will be held in that position until the frame is again tilted in the opposite direction. When the 40 tray is at the outer end of the frame or trackway, the upper portion 47 of the tray may be moved outwardly so as to bring the tray above the door of the car and into the interior thereof. The position of the tray may 45 be regulated through the latching rod 50, as previously set forth. When the tray is to be again delivered back to the serving end of the frame, the tray may be moved back into its position upon its base 48 and the 50 latching finger 90 may be disengaged from the door of the car and the outer end swung laterally. As it moves laterally, the leg 18 will be moved so that the foot 22 will drop off the step portion 27 on to the lower level 55 thereof and as it drops downwardly the outer end will be elevated and the elevation will automatically release the engagement of the finger 64 of the tray frame, thus allowing the tray to slide back to the serving end of the 60 frame.

It is believed that the advantages of this construction will be obvious to those skilled in the art. The frame is so arranged that it may be maintained in a normal balanced condition at all times so that the raising and low-

ering of the frame will be a simple matter and it will be seen that the movement and control of the tray will be practically automatic without particular adjustment. The adjustability of the frame relative to the 70 guide leg 18 makes it possible to regulate the height of the frame to any size of car within which the patrons are seated. It will be particularly convenient in use and economical to 75 operate.

Having thus described my invention, what I claim as new and desire to protect by Letters Patent is:

1. A serving device including a frame, a trackway pivotally suspended on said frame to swing in both vertical and horizontal planes, a tray slidable on said trackway, releasable means at each end of said trackway to engage said tray, said tray being moved by gravity on said trackway when said trackway is tilted.

2. A serving device including a frame, a trackway pivotally suspended on said frame to swing in both vertical and horizontal planes, a tray slidable on said trackway, releasable means at each end of said trackway to engage said tray, said tray being moved by gravity on said trackway when said trackway is tilted, and automatic means operated by the tilting of said trackway to place said tray in approximately horizontal position.

3. A serving device including a frame, a trackway pivotally suspended on said frame to swing in both vertical and horizontal planes, a tray slidable on said trackway, releasable means at each end of said trackway to engage said tray, means operated by the tilting of said trackway to release said means, said tray being moved by gravity on said trackway when said trackway is tilted.

4. A serving device including a supporting frame, mounted to swing on a vertical axis, a trackway supported to tilt thereon, a tray on said trackway and adapted to slide by gravity from one end thereof to the other when said trackway is tilted, a lateral arm on said tray to engage a support, and resilient means to limit the movement of said tray.

5. A serving device including a supporting frame, mounted to swing on a vertical axis, a trackway supported to tilt thereon, a tray on said trackway and adapted to slide by gravity from one end thereof to the other when said trackway is tilted, a lateral arm on said tray to engage a support, resilient means to limit the movement of said tray, and a leg at one end of said trackway adjustable vertically therein to regulate the height thereof.

6. A serving device comprising a frame mounted to swing on a vertical axis, a trackway mounted to rock thereon, a tray frame slidable on said trackway, a tray pivotally mounted on said tray frame, means to latch said tray adjustably on its frame, and auto-

matically operated means to adjust said tray in its frame to maintain said tray in approximately level position.

7. A serving device comprising a frame 5 mounted to swing on a vertical axis, a trackway mounted to rock thereon, a tray frame 10 slidable on said trackway, a tray pivotally mounted on said tray frame, means to latch said tray adjustably on its frame, and means 15 on said trackway engaging said tray to tilt said tray on its frame, said last named means being responsive to the tilting of said trackway.

8. A serving device including a trackway, 15 means to support said trackway between its ends to rock thereon, a tray on said trackway and movable thereon by gravity, means at each end of said trackway engaging said tray to maintain it in position at the end of said 20 trackway and means on said support engaging with means on said trackway to automatically release said tray engaging means controlled by the tilting of said trackway.

9. A serving device including a trackway, 25 means to support said trackway between its ends to rock thereon, a tray on said trackway and movable thereon by gravity, means at each end of said trackway engaging said tray to maintain it in position at the end of said 30 trackway and means to automatically release said tray engaging means controlled by the tilting of said trackway, said tray engaging means also acting to control the angle of said tray relative to said trackway.

35 10. In a serving device of the character stated, a supporting frame, a trackway thereon, a tray slidable on said trackway, and means to vary the height of the outer end of said trackway to position said tray at various 40 levels as desired, said trackway being mounted to swing its outer end laterally, and means to normally hold said trackway in a predetermined position.

45 11. A serving device including a supporting frame, a trackway thereon, a tray slidable on said trackway, and means to swing the tray laterally to position same at various lateral distances as desired.

12. In a device of the character described, a supporting frame pivoted on a vertical 50 axis, a trackway suspended thereon, a tray slidable on said trackway, and means to cause said tray to move from one end of said trackway to the other.

13. In a device of the character described, 55 a supporting frame pivoted on a vertical axis, a trackway suspended thereon between its ends to rock thereon, a tray slidable on said trackway, means to cause said tray to move from one end of said trackway to the 60 other, and releasable means to retain said tray at the ends of said trackway.

14. In a device of the character described, 65 a supporting frame pivoted on a vertical axis, a trackway suspended thereon between its ends to rock thereon, a tray slidable on said trackway, means to cause said tray to move from one end of said trackway to the other, and releasable means to retain said 70 tray at the ends of said trackway, said releasable means being controlled by the position of said trackway upon its support.

15. In a device of the character described, 75 a supporting frame pivoted on a vertical axis, a trackway suspended thereon between its ends to rock thereon, a tray slidable on said trackway, said tray having an extensible member thereon, a latch on said member, and means on said tray to engage a support such as a vehicle frame.

16. In a device of the character described, 80 a supporting frame pivoted on a vertical axis, a trackway suspended thereon between its ends to rock thereon, a tray slidable by gravity on said trackway, the inner end of 85 said trackway being heavier than the outer end, means to control the level to which the inner end of said trackway may descend, means to hold said frame in a predetermined position on its axis operative when said trackway is released to move the said outer end 90 upwardly in the manner described.

In testimony whereof I hereunto affix my signature this 27th day of May, A. D. 1927.

BENJAMIN H. ALLEN.
